UNITED STATES PATENT OFFICE.

JOSEPH A. GROEBLI, OF NEW YORK, N. Y., ASSIGNOR TO KURSHEEDT MANUFACTURING COMPANY, OF NEW YORK, N. Y., A CORPORATION OF NEW YORK.

EMBROIDERING-MACHINE.

SPECIFICATION forming part of Letters Patent No. 717,843, dated January 6, 1903.

Application filed October 28, 1901. Serial No. 80,251. (No model.)

To all whom it may concern:

Be it known that I, JOSEPH A. GROEBLI, a citizen of the United States, residing at New York city, county and State of New York, 5 have invented certain new and useful Improvements in Embroidering Machinery, of which the following is a specification.

My invention relates to embroidering machinery, and has for its object to improve the 10 construction of combined boring and piercing apparatus employed in such machines.

In United States Letters Patent No. 618,458, dated January 31, 1899, I have shown an embroidery-machine structure wherein are 15 combined two sets of mechanisms for making holes in fabric stretched upon a tambour-frame. These means are respectively a set of piercing bore-points having a cutting action and a set of rounded bore-points which 20 serve to give shape to the holes made by the cutting bore-points. In the said patent I have also shown means actuated and controlled from a jacquard mechanism by which either set of bore-points may be positioned 25 for and thrown into action.

It sometimes occurs that in operating an embroidery-machine an operator may not be on her guard or may be inattentive and may have her fingers wounded as the bore-points come into action with a quick motion. 30 In order to increase the protection for operators and for other purposes, I have devised the improvement shown herein.

The main object of this invention is to improve the construction of the positioning mechanism of the bore-points, especially the compensating parts thereof, and also to produce an efficiently-acting mechanism which will position the bore-points at a slow rate of 40 speed—that is, during a period greater than one stitch period.

In the accompanying drawings I have shown one form of apparatus in which my invention is embodied. It will be understood, 45 however, that this apparatus is shown by way of illustration merely and that my invention is not limited thereto.

In the drawings, Figure 1 is an end view of the frame of an embroidery-machine, showing 50 a structure embodying one form of my

invention. Fig. 2 is a front elevation of the said mechanism. Fig. 3 is a front elevation, on an enlarged scale, of the parts at the upper left-hand side of Fig. 2. Fig. 4 is a side view thereof similar to the view shown in Fig. 1. Fig. 5 is a detail view of the actuating-gear; and Fig. 6 is an edge view of the said actuating-gear, partly broken away.

In the drawings, 1 indicates the frame of the embroidery-machine, which may be provided with any desired form of fabric-frame, needle mechanism, and fabric-frame-moving mechanism.

2 represents the jacquard or pattern mechanism, which for the purpose of the present invention may be similar in character to the jacquard mechanism shown in United States Letters Patent No. 528,632, dated November 6, 1894.

3 is the main cam-shaft of the jacquard mechanism, with a suitable cam 4^a carried thereby. The cam-shaft 3 makes one revolution for each stitch and carries a pinion 4, (most clearly shown in Fig. 5 of the drawings,) which pinion is adapted to mesh with a mutilated driving-gear 5. At the points 6 this mutilated gear is denuded of the teeth and is slotted for the passage of movable teeth 7 8, which are carried upon a yoke 9, adapted to be oscillated by an arm 10, so as to project 70 the tooth 8 or the tooth 7, as the case may be, into engagement with the pinion 4. A positioning-bar 11 is pivoted to the gear 5 by its lower end and by its upper end to a setting-bar 12, which is shown as toothed and meshing with pinions 13 14. The pinion 14 is carried on the shaft 15, which is connected to a rocking rail 16, carrying suitable bore-points 17. The pinion 13 is carried upon a shaft 18, connected to a suitable rocking rail 19, carrying bore-points 20. Rotation of the shafts 15 and 18 will cause the rails 16 and 19 to swing and bring their bore-points 17 and 20 into position for use.

A cam 4^a is mounted on the main shaft of the jacquard, and a bowl carried upon one end of a lever 22 operates in the cam-slot 21 therein. The lever 22 is pivoted at 23 and is pivotally connected to the lower end of an operating-bar 24, which is adapted to reciprocate the bore-points when the rail or 90 95 100

bar carrying the bore-points has been rocked to set the bore-points. The bowl of the lever 22 is engaged with the cam at the appropriate time by suitable connections with the jacquard.

- 5 (Not shown.) These connections may be of the construction shown in United States Letters Patent No. 618,458. The upper end of the operating-bar is slotted at 25 (see Fig. 3) and is provided with a connecting-pin 26, (see Fig. 4,) adapted for connection to or disconnection from the operating-arm 27 of the bore-point apparatus. This operating-arm 27 is secured to a rock-shaft 28 and is provided with a curved slot 29, in which the pin 26 is adapted to work. Beyond the lower end of the slot 29 a hole 30 is provided in a block 31, forming part of the operating-arm 27. A connecting-piece 32 is adjustably secured to the operating-arm and is apertured to receive the pin 26 when desired and is adjustable in order to change the initial positions of the apertures. The pin 26 is adapted to be shifted from the aperture in the connecting-piece to the aperture 30 in the operating-arm 27, which arm is swung by the setting and positioning mechanism, as will be described. A lever 33 (see Figs. 3 and 4) is pivoted on a stud 34 and is provided at its upper end with a finger 35, which enters the slot 25 in the upper end of the operating-bar 24. The lower end of the pivoted lever 33 is provided with pins 36, which straddle a cam 37 on the setting-bar 12. The pinion 14 is provided with an arm 38, carrying a pin 39, which is adapted to contact with an arm 40 on the arm 27 to effect the raising of the end of the operating-arm and is also adapted to contact with an arm 27^a on the adjustable piece 32 to lower the end of the operating-arm 27. In this manner the pin 39 effects the adjustment of the operating-arm in order to position the said arm so that the pin 26 can be entered either into the hole in the adjustable piece 32 or the hole 30 in the arm 27.
- 45 The gear 5 is provided with pins 41, adapted to strike the free end of the lever 42, pivoted at 43 and provided with a link connection 44 to a bell 45, so that as the gear commences to rotate to position the bore-points the bell will be struck as a warning signal.

To the frame of the jacquard is secured a suitable cam 46, which is adapted during the movement of the gear 5 to move the yoke 9 to reposition the teeth 7 and 8 for the restoring operation.

The operation of the parts described is as follows: When the bore-points 20 are to be set in action, the jacquard mechanism is suitably actuated to cause the lifter 47 to be raised, thereby swinging the lever 10 on its pivot 48 and depressing the forked end thereof which embraces the pin 50, (or the pin 49,) and thereby forces the lower movable tooth 7 or 8 into engagement with the pinion 4. The motion of the pinion 4 is thus imparted to the gear 5 and rotation of the gear occurs, it being understood that as the gear rotates the pin

50 will run out of the groove in the forked end of the lever 10. As the pinion 4 makes one rotation for each stitch period, the gear 5 will be moved at such speed as to swing the rocking bar or rail 16 slowly. In the machine shown the rocking bar 16 occupies three and one-half stitch periods in turning over. As the gear 5 begins to move the bell 45 will be rung, thus affording a warning signal. The rotation of the gear will cause the positioning-bar 11 to be drawn downward, thus moving the setting-bar 12 downward and rotating the pinions 13 and 14 to swing the rails 16 and 19 over to present the bore-points to the fabric. The downward movement of the setting-bar 12 will effect, through the agency of the cam 37, an outward swing of the lower end of the lever 33. This will cause the upper end of the bar 24 to be swung inwardly—that is, in the direction of the arrow in Fig. 3—and will withdraw the pin 26 from the aperture in the connecting-piece 32. As the pinion 14 rotates it brings the pin 39 carried thereby against the arm or abutment 40 on the operating-lever, swinging the operating-lever upward until the aperture 30 comes opposite the pin 26 on the operating-bar 24, thus effecting a preliminary positioning of the bores. The upper end of the cam 37 now acts upon the lever 33 and causes the pin 26 to be entered into the hole 30. The effect of this movement of the operating-lever 27 is to draw the bore-points rearwardly into operating position, and as the jacquard enters the bowl of the lever 22 into the cam 21 on the jacquard-shaft the operating-bar 24, arm 27, and bore-points 20 are given an oscillating movement to effect the boring operation. The boring operation now continues until at a predetermined time (determined by the jacquard) the parts are restored to their initial positions by a reverse movement, it being understood that in positioning the parts the gear 5 makes a half-revolution until the space 6 is reached, when as the movable tooth 7 has been withdrawn as the tooth 8 was advanced the gear 5 will stop, the tooth 8 striking against a stop 8^a on the frame on the jacquard. During the movement of the gear the cam 46 operates to reset the yoke 9 and to guide the pin 50 into the jaws 51 of bifurcated end of the lever 10.

Having described my invention, what I claim, and desire to secure by Letters Patent, is—

1. In an embroidering-machine organism the combination of the following instrumentalities in operative relation, to wit: bore-points, positioning means for the bore-points, and pattern mechanism controlling the said positioning means, said positioning means including in its structure means for effecting the positioning of the bore-points during a period of time greater than one stitch period of the embroidering mechanism.

2. In an embroidering mechanism, including needle mechanism, the combination of

bore-points, operating means therefor, and means for positioning and withdrawing the said bore-points from operation, including a device for effecting the positioning of the bore-points in advance of the operating period of the bore-points and during a period of time greater than one stitch period of the embroidering-machine.

3. In an embroidering mechanism the combination of bore-point mechanism, including an operating-arm and an operating means therefor and means for moving the arm to position it to effect a connection between the said operating-arm and its operating means and to bring about an initial positioning of the bore-points by the said movement of the said arm.

4. In an embroidering mechanism the combination of a jacquard-shaft, an operating-gear, bore-point-positioning mechanism operated by said operating-gear and pattern-controlled means for giving said operating-gear a partial revolution from the jacquard-shaft during the positioning movement.

25 5. In an embroidering organism, the combination of pattern mechanism, bore-point mechanism, operating means for the said bore-point mechanism including in its structure an operating-bar and an operating-arm and means controlled from a pattern mechanism for connecting the operating arm and bar at two points in succession.

35 6. In an embroidering-machine, the combination of bore-points, bore-point-positioning mechanism, and an alarm actuated before the positioning of the bore-points to give notice that the positioning of the bore-points is about to be effected.

7. In an embroidering-machine the combination of bore-point-positioning mechanism, a pinion performing one revolution for each stitch period of the machine and a gear included in the positioning mechanism adapted to receive motion from the said pinion to effect the positioning during a greater period than a stitch period of the embroidering-machine.

8. An embroidering-machine including in its structure bore-point positioning and operating mechanism, comprised in part by an operating bar and arm and pattern mechanism for controlling the connection and disconnection of the bar and the operating-arm.

9. In an embroidering-machine, the combination, of bore-points, an operating-arm for the bore-points, an operating-bar for the said arm, a pin-and-hole connection between the arm and bar, and automatic means for effect-

ing such a relative movement between the arm and bar as to position the pin and hole elements for engagement with each other.

10. In an embroidering-machine, the combination of bore-point-positioning mechanism, bore-point-operating mechanism, and disconnectible means controlled by the bore-point-positioning mechanism, forming part of the bore-point-operating mechanism and adapted for connecting the bore-point-operating mechanism for action.

11. In an embroidering-machine, the combination of bore-point-positioning mechanism, bore-point-operating mechanism, and means for controlling the positioning mechanism, and disconnectible means controlled by the bore-point-positioning mechanism forming part of the bore-point-operating mechanism and adapted to connect the bore-point-operating mechanism for action.

12. In an embroidering-machine, the combination, of bore-point-operating mechanism, bore-point-positioning mechanism comprised in part by a rotary device operating to position the operating mechanism, and pattern mechanism for controlling the positioning mechanism.

13. In an embroidering-machine, a bore-point-positioning mechanism comprised in part by a bore-point carrier adapted to receive a swinging movement and also a rectilinear movement to effect the positioning of the bore-point carrier and a common rotary device for bringing about both movements.

14. An embroidering-machine comprising in its structure a bore-point carrier and a single common means controlled from a pattern device for imparting to the bore-point carrier a rotary and a reciprocating movement.

15. An embroidering-machine comprising in its structure a bore-point-positioning mechanism including an operating-arm 27 and an operating-bar 24, a pin carried by the bar and engaging the arm and means for shifting the arm to bring an aperture thereof opposite the pin.

16. In an embroidering-machine, the combination of a bore-point carrier, an operating-arm for the bore-point carrier and a common means for swinging the bore-point carrier and moving the operating-arm thereof, comprising in its structure a gear 14, provided with means for moving the operating-arm and connected to the bore-point carrier.
